WORKTABLE TILTING MECHANISM FOR
BLINDSTITCH SEWING MACHINESFrank Parry, Trumbull, Conn., assignor to The
Singer Manufacturing Company, Elizabeth,
N. J., a corporation of New Jersey

Application June 7, 1952, Serial No. 292,261

16 Claims. (Cl. 112—260)

1

This invention relates to blind-stitch sewing machines and it has for its main object to provide improved means for controlling the elevated position of the work-table, whereby the machine may be adjusted to produce blind-stitches in materials having a wide range of thicknesses.

Another object of the invention is to provide an improved work-table tilting mechanism adapting the machine for producing either continuous anchor-strokes or alternate anchor-strokes and skip-strokes.

Still another object of the invention is to provide an improved work-table tilting mechanism having means for determining the normal elevated or anchor-stitch work-presenting position and the lower or skip-stitch work-presenting position of the work-table, said means being constructed so that once the differential between these two positions is determined the initial position of the work-table may be changed without affecting said differential.

A further object of the present invention is to provide a manually controlled abutment-stop, whereby a micrometer adjustment of the normal working position of the work-table can be effected.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 is a top plan view of a machine constructed in accordance with my invention, the bed cover-plate being removed and certain of the parts being in section better to illustrate the details of the machine.

Fig. 2 represents a vertical sectional view taken longitudinally of the base and through the standard and the work-table, illustrating the work-table tilting mechanism and a portion of the throw-out therefor.

Fig. 3 represents a front elevation of the machine-standard with the cover-plate therefor removed and the machine-base and certain of the mechanism extending longitudinally thereof in section to illustrate the drive for the skip-stitch mechanism.

Fig. 4 represents an enlarged horizontal sectional view taken substantially along the line 55

2

4—4, Fig. 3, showing the eccentrically bodied skip-stitch spindle and a portion of the manually actuated connections for effecting a turning adjustment thereof.

5 Fig. 5 represents an enlarged vertical sectional view taken substantially along the line 5—5, Fig. 2, showing the pivotal support for the work-table and the manually retractable throw-out rod for rendering the skip-stitch mechanism inoperative.

10 Fig. 6 represents an enlarged vertical sectional view taken transversely of the work-table adjacent the stitching point to illustrate the relation of the ridge-forming element with the presser-plate and the stitch-forming devices.

15 Fig. 7 represents a vertical sectional view taken longitudinally of the free end of the machine-base, showing the linkage connecting the work-table elevating spring to the work-table.

20 Fig. 8 is a perspective view of the skip-stitch mechanism, together with the work-table elevating coil-spring and the linkage for connecting said coil-spring to the work-table.

25 Referring to the accompanying drawings, the improved sewing machine includes a frame comprising a base or base-arm 10 having a hollow standard 11 rising from the rear right hand corner thereof. Extending laterally towards the left from the upper end of the standard is a horizontal upper arm 12, and extending forwardly from the left hand end thereof is a frame-arm 13. Attached to the free end of the arm is a stationary presser-plate or foot 14 against which the work is clamped by a pair of conventional vertically yieldable work-clamping members 15 carried by a work-table 16 which is supported by the base-arm 10.

30 Journaled in the horizontal upper arm 12 is a main rotary shaft 17 which, through the usual connections disclosed for example in the U. S. patent of Dearborn, No. 705,325, July 22, 1902, oscillates a needle-shaft 18 which is journaled in the forwardly extending arm 13. Carried by the forward end of the needle-shaft 18 is a curved needle 19 which oscillates directly above the presser-plate 14 and in a path transverse to the longitudinal axis thereof; the forward or work-penetrating stroke being from left to right. Cooperating with the needle in the formation of chain-strokes is a looper 20 actuated, in the manner shown in the U. S. patent of Dearborn, No. 639,669, December 19, 1899, from the main-shaft 17. The work is fed rearwardly past the needle 18 by means of a four-motion feed-dog 21 which operates through a hole in the presser-

plate 14 and in opposition to the vertically yieldable work-clamping members 15, all in the manner substantially like that disclosed in the U. S. patent of Dearborn, No. 1,592,446, July 13, 1926.

The work to be stitched is supported on the work-table 16 which is formed at its free left hand end as a tube or horn beneath the stitching and feeding mechanisms and at its right hand end is enlarged into substantially rectangular form having a convex upper surface 22 (Fig. 2), and a pair of depending end-walls 23 and 24 (Figs. 1 and 5). The end walls 23 and 24 are preferably bored to receive the opposite ends of a horizontally disposed pivot-rod or shaft 25 journaled in upstanding lugs 26 and 27 which are integral with a bracket 28 detachably secured by screws 29 to the base 10.

The work-table 16 provides supporting means for the usual ridge-former 30 (Fig. 6) which functions in cooperation with the presser-plate 18 to form a bight in the material facilitating the penetration of the material by the curved needle 19 so as to form blind-stitches. It will be understood that the material is bent or ridged as it is fed over the ridge-former 30 and in order to minimize the friction imposed on the material by the ridge-former during this bending action, the ridge-former is oscillated in the line of feed in a manner such that its forward movement is timed to coincide with the work-advance movement of the feed-dog 21. As will be seen in Figs. 1, 2 and 6, the ridge-former 30 is preferably clamped upon the outer end of a ridge-former carrying shaft 31 journaled in the work-table 16 and having secured to its inner end a rock-arm 32. The rock-arm 32 is connected by a link 33 to the upper end of an upstanding rock-lever 34 secured on the exposed end of a pivot-shaft 35 journaled in one of the side walls of the base 10. Preferably clamped to the inner end of the pivot-shaft 35 is a downwardly extending rock-lever 36 connected by a pitman 37 to an eccentric 38 mounted on the main-shaft 17. Rotation of the main-shaft 17 will impart to the ridge former 30 oscillations about the axis of the ridge-former carrying shaft 31 in timed relation with the stitch-forming and work-feeding mechanisms.

As previously described, the work-table 16 is supported on the pivot-shaft 25 and is spring-biased, by means later to be described, into an elevated work-presenting position. This work-presenting position in the present machine is determined by means of a manually controlled work-table height-adjusting device located in the machine-base 10 and controlled by a thumb-disk located on the upper part of the standard 11 within easy reach of the operator. The work-table height-adjusting device is best shown in Figs. 1 and 2 and comprises a stop-rod 39 endwise slidable in a thickened front wall 40 of the base 10, with its outer or exposed end arranged to be engaged by an adjustable stop-screw 41 threaded into the depending front apron 42 of the work-table 16. The inner end of the stop-rod 39 is secured, as by brazing or the like, to an arched offset head 43 fitted with a horizontal pivot-pin 44 embraced by the forward end of a pitman 45 having its other end enlarged to brace the eccentric body-portion 46 of a skip-stitch or pivot-spindle 47 mounted for limited turning adjustment in the side walls of the standard 11. It will be understood that a slight turning of the skip-stitch spindle 47 will cause its eccentric body-portion 46 to impart a small move-

ment to the pitman 45, which in turn will slide the stop-rod 39 in or out and thereby affect the elevation of the work-table relative to the stitching mechanism. Turning of the skip-stitch spindle 47 is accomplished by means comprising a lever-arm 48 preferably clamped by a screw 49 upon the skip-stitch spindle 47 (Figs. 2 and 4). Pivotally connected to the end of the lever-arm 48 is the lower end of a link 50 which is preferably bifurcated at its upper end to straddle and pivotally support a traveling-nut 51 into which is threaded an adjusting stud 52 rotatably journaled in an upwardly inclined portion 53 of a cover-plate 54 detachably secured and closing the front wall of the machine-standard 11. The exposed end of the adjusting stud 52 is squared, as at 55, and projects into a thumb-disk 56 locked on the adjusting stud 52 by a cap-screw 57 threaded into the adjusting stud. The thumb-disk 56 is scribed adjacent its periphery with indicia disposed to cooperate with a fixed pointer (not shown) on the machine-frame in order to facilitate setting the work-table 16 to its proper elevation. It will be appreciated that a manual turning of the thumb-disk 56 will effect a rise or fall in the elevation of the work-table 16, the traveling-nut 51 on the adjusting stud 52 being irreversible so that no additional locking means is necessary for maintaining the work-table in its selected position of adjustment.

In blind-stitch machines of the type illustrated in the drawings, it is common to equip them with skip-stitch mechanism by which the machine can produce skip-stitches as well as anchor-stitches. Skip-strokes are produced in the present machine automatically by periodically tilting the work-table so that its free end moves for a limited extent in a direction downwardly or away from the stitching mechanism. The skip-stitch mechanism, best shown in Figs. 2, 4 and 8, includes an endwise reciprocating plunger indicated generally as 58. The plunger 58 is journaled in the thickened front wall 40 of the machine-base 10 and is connected at its rear end to one end of a pitman-connector 59 suitably formed at its other end to embrace a needle-bearing 60 mounted on a skip-stitch eccentric 61 preferably formed integral with a belt-sprocket 62 journaled on the eccentric body-portion 46 of the skip-stitch spindle 47. The belt-sprocket 62 is driven by a clip-beit 63 from a smaller belt-sprocket 64 secured on the main-shaft 17. Rotation of the main-shaft 17 imparts to the skip-stitch eccentric 61 rotary motion at one-half the speed of rotation of the shaft 17, and the skip-stitch eccentric through the pitman-connector 59 imparts an endwise reciprocation to the skip-stitch plunger 58. Opposing the plunger 58 is an adjustable abutment-screw 65 which is threaded into the depending apron 42 of the work-table 16.

The skip-stitch plunger 58, as it is reciprocated, strikes the abutment-screw 65 and swings the work-table 16 about its pivot 25 in opposition to a yielding force imposed by a work-table elevating coil-spring 66 which acts between the pitman-connector 59 and the work-table apron 42. As will be seen in Figs. 2 and 8, the coil-spring 66 at its inner end is hooked to a cross-pin 67 provided in a spring-connector 68 freely journaled on a spring-tension-regulating screw 69 threaded into the offset rear end 70 of the pitman-connector; access to the spring-tension-regulating screw 69 being had through an open-

is turned the eccentric bodied skip-stitch spindle 47 is turned and, as a result of the eccentric body thereof, the center distance between the spindle 47 and rotary shaft 11 is changed. This change in center distance is very small and can readily be accommodated by the clip-belt 62.

Having thus set forth the nature of the invention, what I claim herein is:

1. In a blind-stitch sewing machine, a main frame having a base, a standard and an overhanging arm, of a work-table movably mounted on said base and having a portion underlying the free end of said overhanging arm, an actuating shaft journaled in said main frame, an actuator driven by said shaft, work-table moving means providing for moving said work-table in one direction relative to said overhanging arm and including a member operatively connected to said actuator, and means acting in opposition to said work-table moving means including a spring operatively connected at one end to said work-table and at its other end to said member.

2. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, an actuating shaft journaled in said main frame, an actuator driven by said shaft, work-table moving means providing for periodically moving said work-table in a direction away from said stop and including a member connected to said actuator, and a spring operatively connected at one end to said work-table and at its other end to said member to bias said work-table toward and into contact with said stop.

3. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, a rotary shaft journaled in said main frame, an eccentric driven by said rotary shaft, work-table moving means providing for moving said work-table in a direction away from said stop and including a member embracing said eccentric, a spring operatively connected at one end to said work-table and at its other end to said member to bias said work-table into contact with said stop, and means for regulating the pressure exerted by said spring.

4. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, a spring for biasing said work-table toward said stop, an actuating shaft journaled in said main frame, work-table moving means operated by said actuating shaft and providing for periodically moving said work-table away from said stop in opposition to said spring, said work-table moving means including a reciprocatory plunger movable into and out of engagement with said work-

table and comprising two interconnected sections having relatively extended and contracted positions, and manually operated means providing for shifting said plunger sections from their relatively extended position in which said plunger periodically engages said work-table to their relatively contracted position in which said plunger does not engage said work-table.

5. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, a spring for biasing said work-table toward said stop, an actuating shaft journaled in said main frame, work-table moving means operated by said actuating shaft and providing for periodically moving said work-table away from said stop in opposition to said spring, said work-table moving means including a reciprocatory plunger movable into and out of engagement with said work-table and comprising telescopically arranged inner and outer sections having relatively extended and contracted positions, and means providing for at will relatively shifting said plunger sections from their extended position in which said plunger periodically engages said work-table to their contracted position in which said plunger does not engage said work-table.

6. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, a spring for biasing said work-table toward said stop, an actuating shaft journaled in said main frame, work-table moving means operated by said actuating shaft and providing for periodically moving said work-table away from said stop in opposition to said spring, said work-table moving means including a reciprocatory plunger movable into and out of engagement with said work-table and comprising two interconnected sections having relatively extended and contracted positions, and cam means in operative engagement with each of said plunger sections and operable to relatively move said plunger sections from their contracted to extended position.

7. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, a spring for biasing said work-table toward said stop, an actuating shaft journaled in said main frame, work-table moving means operated by said actuating shaft and providing for periodically moving said work-table away from said stop in opposition to said spring, said work-table moving means including a reciprocatory plunger movable into and out of engagement with said work-table and comprising telescopically arranged inner and outer sections having relatively extended and con-

ing 71 closed by a screw-plug 72. As will be seen in Figs. 7 and 8, the front end of the coil-spring 66 is secured to the inner end of a slide-rod 73 supported in the end-wall 40 of the base 19 and connected at its outer end by a short link 74 to one side face of a rock-member 75 which is pivotally mounted on a stud 76 threaded into the upstanding lug 26 (Fig. 5) of the bracket 28. Connected to the other side face of the rock-member 75 is a link 77 connected to the depending apron 42 of the work-table 16. The linkage, including the slide-rod 73, rock-member 75 and links 74 and 77, provides means such that when the work-table is lowered by manual actuation of the usual knee-shift, the effort required by the operator becomes less as the work-table approaches its lowered position. This feature is fully described and claimed in another of my U. S. patent applications, Serial No. 292,264, filed here-with and reference may be had to that application for a more complete description of the same.

From the foregoing, it will be appreciated that the normal elevated work-presenting position of the work-table is determined by the position of the stop-rod 39 and the selected position of adjustment of the stop-screw 41. It will be further appreciated that the work-table 16 is biased about its pivot 25 so that the stop-screw 41 is maintained against the end of the stop-rod 39 by the coil-spring 66 which acts between the pitman-connector 59 and the apron 42 of the work-table 16. Inasmuch as the coil-spring 66 acts between the pitman-connector 59 and the work-table 16, rather than between the base 18 of the machine-frame and the work-table, the tension developed by the coil-spring 66 is not transmitted to the skip-stitch eccentric 61, which additional tension or pressure would increase the friction at the bearing points between the pitman-connector 59 and the eccentric 61, thereby increasing the wear on the parts.

In order that the machine may be adjusted to sew either continuous anchor-stitches or anchor-stitches and skip-stitches, throw-out means are provided whereby the endwise reciprocatory skip-stitch plunger 58 can be rendered ineffective or effective in tilting the work-table 16. In the present machine, the skip-stitch plunger 58 is adapted to reciprocate through a fixed amplitude which depends upon the eccentricity of the skip-stitch eccentric 61. Throw-out of the skip-stitch mechanism is accomplished by shortening the length of the skip-stitch plunger 58 so that it falls short of contacting the abutment-screw 65 during its reciprocatory movement. The throw-out device is best shown in Figs. 2, 5 and 8, and comprises arranging the skip-stitch plunger 58 in two telescopically arranged parts, an outer tubular section or sleeve 78 which is connected directly to the pitman-connector 59 and an inner section or plunger 79 disposed to directly engage the abutment-screw 65. The inner plunger 79 is journaled in the outer sleeve member 78 for both turning movement and endwise sliding movement. As will be seen in Fig. 2, the bore of the outer sleeve member 78 is enlarged to provide clearance for a compression spring 80 which acts between a shoulder on the shell member and the head of a cap-screw 81 threaded into the end of the inner plunger 79 for the purpose of biasing the outer and inner members of the skip-stitch plunger toward each other into their contracted or telescoped position. Mounted on the inner plunger member 79, adjacent its exposed end, is a collar 82 having an inclined cam face 83 which

is yieldingly biased by the coil-spring 80 into engagement with the pointed end of a projection 84 extending from the proximate end-face of the outer sleeve member 78. The collar 82 has cut into its periphery suitable gear teeth 85 which are in mesh with a rack 86 cut into the bottom of an endwise slidable throw-out rod 87 journaled in the bearing lugs 26 and 27 of the bracket 28. The throw-out rod 87 at one end is provided with a hand-knob 88 and at its other end is fitted with a stop-collar 89 which limits the retracting of the throw-out rod. Turning of the throw-out rod 87 is prevented by a guide-screw 90 (Fig. 5) whose reduced inner end enters a narrow guide-groove 91 formed in the throw-out rod. From the foregoing, it will be obvious that with the inner plunger 79 and the outer sleeve member 78 of the skip-stitch plunger 58 locked in their relatively extending position, determined by the projection 84 seated in a detent notch 92 formed in the cam face 83 of the collar 82, rotation of the skip-stitch eccentric 61 will impart an endwise reciprocation to the composite skip-stitch plunger 58, which plunger 58 will periodically engage the abutment-screw 65 and tilt the work-table 16 about its pivot 25. This tilting of the work-table will cause the ridge-former 30 to rise and fall relative to the presser-plate 14, resulting in the formation of skip-stitches and anchor-stitches. When it is desired to produce successive anchor-stitches, a manual withdrawal of the throw-out rod 87 will, through the rack 86 and gear 85, effect a clockwise turning of the inner plunger 79, causing the collar 82 to turn relative to the outer sleeve member 78 of the skip-stitch plunger. It will be appreciated that the detent means (projection 84 and cooperating detent notch 92) releases under the pressure created by the withdrawing of the throw-out rod 87. When the collar 82 turns relative to the outer sleeve member 78 the inclined cam face 83 contacted by the end of the projection 84 permits the inner and outer members of the skip-stitch plunger to move, under the action of the compression spring 80, into their contracted or telescoped position. In this telescoped position, the skip-stitch plunger 58 undergoes its usual reciprocatory movements, but the overall length of the plunger is shortened to the extent that the end of the inner plunger 79 does not contact the abutment-screw 65. It will be understood that the stop-rod 39 and stop-screw 41 cooperate to locate the work-table 16 in its proper elevated anchor-stitch position and that, when the two members of the skip-stitch plunger 58 are in their relatively separated or extended position, the plunger 78 and abutment-screw 65 cooperate to tilt the work-table and thereby locate it in its skip-stitch position. As will be observed in Fig. 4, the eccentric bodied pivot-spindle 47 provides a common support for the adjustable stop-rod link 45 and skip-stitch eccentric 61 and, consequently, a slight turning of the spindle 47, occasioned by the manual turning of the thumb-disk 56, will turn the skip-stitch spindle 47 and simultaneously adjust the position of both the skip-stitch plunger 58 and the stop-rod 39 relatively to their respective screws 65 and 41. Thus, the selected initial differential in elevation of the work-table between its anchor-stitch position and its skip-stitch position is not affected during the turning of the thumb-disk 56, but rather the work-table 16 is tilted through the same arc at a different elevation relative to the stitching mechanism. It will be observed in Fig. 2 for instance, that when the thumb-disk 56

tracted positions, and means providing for at will relatively shifting said plunger sections from their extended position in which said plunger periodically engages said work-table to their contracted position in which said plunger does not engage said work-table, said last named means including a spring acting between said plunger sections for biasing them in one direction relatively to each other, and a cam in operative engagement with each of said plunger sections and operable to relatively move said plunger sections in the other direction.

8. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, a spring for biasing said work-table toward said stop, an actuating shaft journaled in said main frame, work-table moving means operated by said actuating shaft and providing for periodically moving said work-table away from said stop in opposition to said spring, said work-table moving means including a reciprocatory plunger movable into and out of engagement with said work-table and comprising telescopically arranged inner and outer sections having relatively axially extended and contracted positions, and means providing for relatively shifting said plunger sections axially of each other, said last named means including a collar mounted on one of said plunger sections and having a cam-shaped end-face disposed for engagement by the other of said plunger sections, a manually retracted throw-out member operatively connected to said collar to effect a turning of the collar when said throw-out member is moved, and a spring acting between said inner and outer sections to maintain said plunger section in contact with the cam-shaft end-face of said collar.

9. In a blind-stitch sewing machine, a main frame having a base, a standard and an overhanging arm, and stitch-forming mechanism in said overhanging arm, of a work-table movably mounted on said base and having a portion underlying the free end of said overhanging arm, a stop for determining the elevated work-presenting position of said work-table relative to said stitch-forming mechanism, a spring for biasing said work-table toward said stop, an actuating shaft journaled in said main frame, work-table moving means operated by said actuating shaft and providing for periodically moving said work-table away from said stop in opposition to said spring, said work-table moving means including a reciprocatory plunger movable into and out of engagement with said work-table and comprising telescopically arranged inner and outer sections having a relatively axially extended operative position and a contracted inoperative position, and means providing for relatively shifting said plunger sections axially of each other from one to the other end of said positions, said last named means including a peripherally toothed collar mounted on said inner plunger section and having a cam-shaped end-face disposed for engagement by the proximate end of said outer plunger section, a manually retracted throw-out rod provided with a rack in mesh with the peripheral teeth of said collar to effect a turning of the collar when said throw-out rod is

moved, a spring acting between said inner and outer sections to maintain said outer plunger section in contact with the cam-shaped end-face of said collar, and detent means for holding said inner and outer plunger sections in their extended operative position.

10. A blind-stitch sewing machine having a main frame including a base, a standard and an overhanging arm, stitch-forming mechanism in said overhanging arm, a work-table movably mounted on said base and having a portion underlying the free end of said overhanging arm, a movable stop mounted in said base and disposed to be engaged by said work-table to locate the latter in its elevated work-presenting position, a spring for biasing said work-table into contact with said stop, an eccentric located in said main frame and supported for turning adjustment, a pitman connected at one end to said movable stop and at its other end to said eccentric, and means for adjusting said eccentric including a thumb-disk mounted on said main frame.

11. A blind-stitch sewing machine having a main frame including a base, a standard and an overhanging arm, stitch-forming mechanism in said overhanging arm, a work-table movably mounted on said base and having a portion underlying the free end of said overhanging arm, a movable stop member mounted in said base and disposed to be engaged by said work-table to locate the latter in its elevated work-presenting position, a spring for biasing said work-table into contact with said stop, an eccentric mounted within the lower portion of said standard and supported for turning adjustment, means operatively connecting said stop member to said eccentric, and means for turning said eccentric including a manually operable element located adjacent the top of said standard.

12. A blind-stitch sewing machine having a main frame including a base, a standard and an overhanging arm, stitch-forming mechanism in said overhanging arm, a work-table movably mounted on said base and having a portion underlying the free end of said overhanging arm, a movable stop member mounted in said base and disposed to be engaged by said work-table to locate the latter in its elevated work-presenting position, a spring for biasing said work-table into contact with said stop, a pivot-spindle mounted for turning movement in said standard, an eccentric mounted on said spindle, means operatively connecting said stop member to said eccentric, and manually operable means located on said standard and operatively associated with said pivot-spindle for turning the same and thereby adjusting the position of said stop-member.

13. A blind-stitch sewing machine having a main frame including a base, a standard and an overhanging arm, stitch-forming mechanism in said overhanging arm, a work-table movably mounted on said base and having a portion underlying the free end of said overhanging arm, a movable stop member mounted in said base and disposed to be engaged by said work-table to locate the latter in its elevated work-presenting position, a spring for biasing said work-table into contact with said stop, a pivot-spindle mounted for turning movement in said standard and having an eccentric provided thereon, means operatively connecting said stop-member to said eccentric, a rock-arm secured to said pivot-spindle, and a manually operable member located on said standard and operatively connected to said rock-

arm to provide for turning the pivot-spindle and thereby adjusting the position of said stop-member.

14. A blind-stitch sewing machine having a main frame including a base, a standard and an overhanging arm, stitch-forming mechanism in said overhanging arm, a rotary shaft journaled in said main frame, a work-table movably mounted on said base and having a portion underlying the free end of said overhanging arm, and means for moving said work-table relative to said overhanging arm, said means including a movable abutment member disposed to engage said work-table, an eccentric mounted for rotation within said main frame, driving mechanism operatively connecting said abutment member to said eccentric, and means for rotating said eccentric including a driving belt connection with said rotary shaft.

15. A blind-stitch sewing machine having a main frame including a base, a standard and an overhanging arm, stitch-forming mechanism in said overhanging arm, a rotary shaft journaled in said main frame, a work-table movably mounted on said base and having a portion underlying the free end of said overhanging arm, and means for moving said work-table relative to said overhanging arm, said means including a movable abutment member disposed to engage said work-table, a pivot-spindle journaled for turning movement in said main frame and having an eccentrically disposed portion provided thereon, a driven eccentric journaled for rotation on the eccentrically disposed portion of said pivot-spindle, means operatively connecting said abutment member to said eccentric, a driving belt connecting said eccentric to said rotary shaft, and manually actuated connections associated

with said pivot-spindle for turning the latter and thereby adjusting the position of action of said abutment member.

16. A blind-stitch sewing machine having a main frame including a base, a standard and an overhanging arm, stitch-forming mechanism in said overhanging arm, a rotary shaft journaled in said main frame, a work-table movably mounted on said base and having a portion underlying the free end of said overhanging arm, a movable stop member mounted in said base, means for yieldingly maintaining said work-table in contact with said stop-member, a movable abutment member periodically operated to engage said work-table and move it away from said stop member in opposition to said yieldable means, a pivot-spindle journaled for turning movement in said main frame and having an eccentrically disposed portion provided thereon, a pitman connected at one end to said stop-member and at its other end formed to embrace said eccentrically disposed portion on said pivot-spindle, a driven eccentric journaled for rotation on said eccentrically disposed portion on said pivot-spindle, means operatively connecting said abutment member to said eccentric, driving means connecting said eccentric to said rotary shaft, and manually actuated connections associated with said pivot-spindle for turning the latter and thereby simultaneously adjusting said stop member and the position of action of said abutment member.
